Specification for Design.

Patented Feb. 20, 1917.

Application filed November 25, 1912. Serial No. 733,535. Term of patent 14 years.

To all whom it may concern:

Be it known that I, GEORGE B. THOMAS, a citizen of the United States of America, residing at Bridgeport, in the county of Fairfield and State of Connecticut, have invented a new, original, and ornamental Design for a Fuse-Plug Cap, of which the following is a specification, reference being had to the accompanying drawing, forming part thereof, in which—

Figure 1 is a side elevation of a cap with the plug body shown in dotted lines;

Fig. 2 is a plan view of the cap alone; and Fig. 3 is a perspective of the plug with the portions below the cap shown in dotted lines, as in Fig. 1.

I claim:

The ornamental design for a fuse plug cap, as shown.

GEORGE B. THOMAS.
